Patented May 14, 1968

211,028

ANTENNA HOUSING

Bruno Zucconi, 3101 Marina Drive,
Alameda, Calif. 94501

Filed Sept. 19, 1967, Ser. No. 8,648

Term of patent 14 years

(Cl. D26—14)

Fig. 1

Fig. 2

Fig. 3Fig. 6Fig. 5Fig. 4

FIG. 1 is a front perspective view of an antenna housing showing my new design;

FIG. 2 is a rear perspective view thereof;

FIG. 3 is a front elevation thereof;

FIG. 4 is an elevational view as seen in the direction of line 4-4 in FIG. 3;

FIG. 5 is a view as seen in the direction of line 5-5 in FIG. 4; and

FIG. 6 is an end elevation as seen in the direction of lines 6-6 in FIG. 4.

I claim:

The ornamental design for an antenna housing, as shown.
